Specification for Design.

Patented July 17, 1917.

Application filed May 14, 1917. Serial No. 168,609. Term of patent 14 years.

To all whom it may concern:

Be it known that I, CHARLES BLESCH, a citizen of the United States, residing at Newport, in the county of Campbell and State of Kentucky, have invented a new, original, and ornamental Design for Corner-Pieces for Burial-Caskets, of which the following is a specification, reference being had to the accompanying drawing, forming part thereof.

My new, original and ornamental design for a corner-piece for burial-caskets is shown in the accompanying drawing, in which,

Figure 1 is a front elevation of one side

of the corner-piece for burial-caskets, showing my new design; and

Fig. 2 is an elevation of a corner-piece for burial-caskets, showing my new design, the line of vision being directed toward the angle of the corner thereof.

I claim:

The ornamental design for a corner-piece for burial-caskets, substantially as shown.

CHARLES BLESCH.
